(57) **CLAIM**

The ornamental design for a heat exchange plate as shown and described.

DESCRIPTION

1. Heat exchange plate

1.1 : Perspective

1.2 : Perspective

1.3 : Front

1.4 : Back

1.5 : Left

1.6 : Right

1.7 : Top

1.8 : Bottom

1.9 : Enlarged Partial View

1.10 : Enlarged Partial View

1.11 : Perspective

Reproduction 1.9 is an enlarged partial view of a portion defined by boundary lines in reproduction 1.1; reproduction 1.10 is an enlarged partial view of a portion defined by boundary lines in reproduction 1.1; reproduction 1.11 is a perspective view where elements forming no part of the claimed design are removed; the dash-dash broken lines in the drawings depict portions of the heat exchange plate which form no part of the claimed design; the dot-dash broken lines in the drawings depict the boundaries of the

(Continued)

enlarged partial views that form no part of the claimed design; the labels **1.9** & **1.10** in reproduction **1.1** form no part of the claimed design.
